(57) **CLAIM**

The ornamental design for a set of modular data cable components, as shown and described.

DESCRIPTION

FIG. 1 is an isolated front, right, and top perspective view of the first component of the set of modular data cable components shown in FIG. 53;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is an enlarged top plan view thereof;

FIG. 8 is an enlarged bottom plan view thereof;

FIG. 9 is an isolated front, right, and top perspective view of the second component of the set of modular data cable components shown in FIG. 53;

FIG. 10 is a rear, left and bottom perspective view thereof;

FIG. 11 is a front view thereof;

FIG. 12 is a rear view thereof;

FIG. 13 is a left side view thereof;

FIG. 14 is a right side view thereof;

FIG. 15 is an enlarged top plan view thereof;

FIG. 16 is an enlarged bottom plan view thereof;

FIG. 17 is an isolated front, right, and top perspective view of the third component of the set of modular data cable components shown in FIG. 53;

FIG. 18 is a rear, left and bottom perspective view thereof;

FIG. 19 is a front view thereof;

FIG. 20 is a rear view thereof;

FIG. 21 is a left side view thereof;

FIG. 22 is a right side view thereof;

FIG. 23 is an enlarged top plan view thereof;

FIG. 24 is an enlarged bottom plan view thereof;

(Continued)

FIG. 25 is an isolated front, right, and top perspective view of the fourth component of the set of modular data cable components shown in FIG. 53;
 FIG. 26 is a rear, left and bottom perspective view thereof;
 FIG. 27 is a front view thereof;
 FIG. 28 is a rear view thereof;
 FIG. 29 is a left side view thereof;
 FIG. 30 is a right side view thereof;
 FIG. 31 is an enlarged top plan view thereof;
 FIG. 32 is an enlarged bottom plan view thereof;
 FIG. 33 is an isolated front, right, and top perspective view of the fifth component of the set of modular data cable components shown in FIG. 53;
 FIG. 34 is a rear, left and bottom perspective view thereof;
 FIG. 35 is a front view thereof;
 FIG. 36 is a rear view thereof;
 FIG. 37 is a left side view thereof;
 FIG. 38 is a right side view thereof;
 FIG. 39 is an enlarged top plan view thereof;
 FIG. 40 is an enlarged bottom plan view thereof;
 FIG. 41 is an isolated front, right, and top perspective view of the sixth component of the set of modular data cable components shown in FIG. 53;
 FIG. 42 is a rear, left and bottom perspective view thereof;
 FIG. 43 is a front view thereof;
 FIG. 44 is a rear view thereof;
 FIG. 45 is a left side view thereof;
 FIG. 46 is a right side view thereof;
 FIG. 47 is an enlarged top plan view thereof;
 FIG. 48 is an enlarged bottom plan view thereof;
 FIG. 49 is a perspective view of the set of modular data cable components shown in FIG. 53, where the components shown in FIGS. 1, 9, and 41 are shown in a state of use, isolated from the remaining components of the set;
 FIG. 50 is a perspective view of the set of modular data cable components shown in FIG. 53, where the components shown in FIGS. 1, 9, and 33 are shown in a state of use, isolated from the remaining components of the set;
 FIG. 51 is a perspective view of the set of modular data cable components shown in FIG. 53, where the components shown in FIGS. 1, 9, and 17 are shown in a state of use, isolated from the remaining components of the set;

FIG. 52 is a perspective view of the set of modular data cable components shown in FIG. 53, where the components shown in FIGS. 1, 9, and 41 are shown in a state of use, isolated from the remaining components of the set; and, FIG. 53 is a front view of a set of modular data cable components, showing my new design.

Dot-Dash broken lines represent a symbolic break in the article's length and form no part of the claimed design. All other broken lines depict portions of the set of modular data cable components which form no part of the claimed design. One component of the set of modular data cable components is shown with a symbolic break in its length. The appearance of any portion of the article in between the broken symbolic break lines, including the broken symbolic break lines themselves, forms no part of the claimed design.
